NECKTIE PRESS AND HOLDER

Anthony Alvin Baur, Monroe, La.

Application March 14, 1949, Serial No. 81,306

3 Claims. (Cl. 206—7)

1

This invention relates to necktie carriers, and more particularly to an improved, combined carrier and press.

The general object of the invention is to provide a device of this character comprising a carrying case having a plurality of separate, individual removable tie holders assembled therein, each tie holder being in the nature of a press.

A specific object is to devise improved means for securing the holders in the case, so that they may be readily removed when desired, without the necessity of releasing any fastening device.

Another object is to provide improved means for securing the holders in the case, so that they may be individually removed when desired, without the necessity of removing any other of the holders secured therein.

A further specific object of the invention is to provide a simple and convenient construction of holder, into and from which a tie may be readily inserted and removed, and which will serve to effectively press the tie so as to keep it smooth and free from wrinkles at all times.

With the above and other objects in view, and to improve generally on the details of such apparatus, the invention consists in the construction, arrangement and combination of parts herein-after described and claimed, and illustrated in the accompanying drawings, forming part of this specification, and in which:

Fig. 1 is a perspective view of my improved carrying case in open position with a single tie holder secured therein;

Fig. 2 is a perspective view of one of the individual tie holders which I employ;

Fig. 3 is a plan view showing the carrying case with one or more holders in position therein;

Fig. 4 is a transverse section substantially on the line 4—4 of Fig. 3, looking in the direction of the arrows;

Fig. 5 is a transverse section on an enlarged scale substantially on the line 5—5 of Fig. 3, looking in the direction of the arrows; and

Fig. 6 is a fragmentary elevation on a still larger scale showing one of the fastening means employed with the tie holder to secure the leaves together, with a portion of the upper leaf cut away.

Referring to the drawings in detail, my improved carrying case comprises a body portion, indicated generally by the reference numeral 6, and a cover portion, indicated generally at 7, while one of a plurality of tie holders which may be secured within the case is indicated generally at 8. The body and cover portions of the case

2

are shaped in a preferred embodiment of my invention to present a smoothly contoured appearance when the cover is closed, as shown in Fig. 3, and elongated in general conformity with the outline of a folded tie. Any suitable material may be used in its manufacture, although I have shown it in the drawings as being constructed of a transparent plastic material which permits ready inspection of the contents.

The body portion 6 of the case includes spaced top and bottom walls 9 and 10, respectively, spaced straight side walls 11 and 11^a, and an end wall 12. The cover portion 7 includes top wall 13 and a continuous side wall 14, and is joined to the body portion by hinge means 15. It will be observed that when the cover 7 is closed, side wall 14 extends between the side wall elements 11 and 11^a, and the extending portion 10^a of the bottom wall 10 serves as a bottom co-operating with the side walls 14 of the cover portion 7, to effect a closure.

The tie holders 8, one of which is shown in Fig. 2, comprise substantially flat leaves 16 and 17, which may be detachably secured together in spaced overlying relationship by fastening means 18 attached to leaf 16, in order to receive between them an article of clothing such as a folded tie (not shown). As shown in Fig. 6, the fastening means may comprise a pin having an upright shank portion 18^a and a head portion 18^b, the shank being screwed or riveted by conventional methods to leaf 16. A helical spring 18^c surrounds the shank 18^a and bears against a small plate or washer 17^a which slides freely on the shank. A pair of aligned slots, extending into the margins of opposite ends of leaf 17, each define pairs of ears 19 and 20, which engage under the spring-pressed plates 17^a when leaf 17 is put in place. While any thin material may be used in the manufacture of the leaves 16, and 17, I preferably use plastic sheets for convenience and appearance. In practice, leaf 11 should have a certain amount of flexibility in order to permit detachable engagement with fastening means

18. Customarily, when a tie is to be placed in the holder, the leaves are first detached, and the tie folded and laid flat on leaf 16, after which leaf 17 is bowed downwardly to permit the ear portions 19 and 20 to be inserted under the plates 17^a of the fastening means. When released, the leaf 17 resumes a substantially flat position to hold the tie in place under a slight pressure. In order to prevent the formation of creases in the tie, spacers 21 may be attached at opposite ends of leaf 17, and it may also be desirable to apply

strips 22 of non-slipping material, such as rubber, to the inner surfaces of both leaves to assist in maintaining a tie in position.

The contour of each leaf 16 is substantially similar in outline to body portion 6 of the carrying case. It is symmetrical with respect to its lateral axis, having side edges which tend toward convergence in both directions from a line perpendicular to the longitudinal axis but lying to one side of the center of that axis. This results in a pair of short sides 16^a and 16^b which tend toward convergence in one direction, and a pair of longer straight sides 23, and 24, which tend toward symmetrical convergence in the opposite direction. The side 16^a is offset inwardly with respect to side 23, and side 16^b and similarly inwardly offset from side 24 to define respectively transversely disposed end portions 23^a and 24^a for the marginal edges 23 and 24.

In order to secure a plurality of tie holders 8 within the case in stacked, spaced relationship, a plurality of substantially parallel longitudinally extending grooves 25 and 25^a are provided in side walls 11 and 11^a respectively, for slidable engagement with marginal edges 23 and 24 of the tie holders. By virtue of this arrangement, individual tie holders may be inserted and removed without disturbing other tie holders within the case. Furthermore, it is not necessary to fill the case in order to prevent movement, or jumbling of the contents; a single tie holder will remain in place as securely as when the case is full. This is assured, not only because each tie holder is engaged by individual grooves in the side walls provided for its support, but also because end portions 23^a and 24^a will abut against the ends 14^a and 14^b of side wall 14, when the cover 1 is closed. The cover may be secured in closed position by a pivoted latch means 26.

What I claim is:

1. A tie carrier for a plurality of individual tie holders each of which is provided with a pair of marginal edges for supporting the holders in stacked spaced relationship comprising a case having a body portion and a cover portion, said body portion including spaced flat top and bottom walls permanently joined along portions of their peripheries by spaced inwardly converging, flat, side wall elements, said bottom wall projecting longitudinally beyond the ends of said side wall elements and being of outwardly tapering form, means on said side wall elements for sliding engagement with said marginal edges of said tie holders, said cover portion including a U-shaped side wall of substantially the same width as the side wall elements of said body portion and extending between the ends of the latter portion to enclose one of the ends of said tie holders and a top wall attached to the side wall of the cover portion and hingedly joined to the top wall of said body portion.

2. A tie carrier for a plurality of individual tie holders each of which comprises a pair of leaves between which a folded tie may be received, and each of which is provided with a pair of marginal edges for supporting the holders in stacked

spaced relationship comprising a case having a body portion and a cover portion, said body portion including spaced flat top and bottom walls permanently joined along portions of their peripheries by spaced converging, flat side wall elements, said wall elements being provided with a plurality of spaced grooves disposed in planes substantially parallel to said bottom wall for the reception of the marginal edges of said tie holders, said bottom wall and the ends of said tie holders both projecting longitudinally beyond the ends of said side wall elements, and both being of outwardly tapering form, said cover portion including a continuous, flat side wall of substantially the same width as the side wall elements of said body portion and extending between the ends of the latter, and a flat top wall permanently secured to said continuous side wall and hingedly joined to the top wall of said body portion, said side wall and flat top of said cover portion conforming with the shape of the longitudinally projecting ends of said bottom wall and said tie holders, and enclosing said ends of the tie holders.

3. A tie carrier for a plurality of individual tie holders each of which is provided with a pair of marginal edges for supporting the holders in stacked spaced relationship comprising a case having a body portion and a cover portion, said body portion including spaced, flat top and bottom walls permanently joined along portions of their peripheries by spaced, flat side wall elements, said bottom wall projecting longitudinally beyond the ends of said side wall elements, and being of outwardly tapering form, and said side wall elements having a plurality of spaced grooves disposed in planes substantially parallel to said bottom wall for the reception of the marginal edges of said tie holders, said cover portion including a continuous, flat side wall element extending between the ends of the side wall elements of said body portion, said continuous, flat, side wall element of the cover conforming with the shape of but being free from the longitudinally projecting portion of said bottom wall, and a top wall permanently attached to said side wall element of the cover portion and hingedly joined to the top wall of said body portion.

ANTHONY ALVIN BAUR.
